By their Attorney, Thaw and Field.

UNITED STATES PATENT OFFICE

MAURICE A. KONIKOFF AND HARRY R. KONIKOFF, OF NEW YORK, N. Y.

DISPLAY DEVICE

Application filed May 27, 1926. Serial No. 111,901.

Our invention relates to improvements in display devices, and more particularly has reference to a suitable form of stand or support for exhibiting footwear.

5 Referring to the accompanying drawings, Fig. 1 illustrates in perspective, part being broken away, a suitable form of display stand, embodying an application of our invention. Fig. 2 is a detail of one of the bearings thereof.

3 indicates the base, preferably provided with rubber buttons 4, and 5 is a tube secured therein, and is provided at the top with a socket portion 6, through which the adjusting screw 7 projects to bind the stem 8 adapted to telescopically slide therein, said stem having secured at the top a split block 9, with a transverse bore 10, from which the split 11 extends to the outside of the same, said block 15 being also drilled and tapped at right angles thereto, as indicated in dotted outline at 12, to receive the thumb screw 13.

14 indicates the upper support which is preferably stamped from sheet metal, having 25 turned down ears or bearings 15, adapted to pass over the block 9, and having holes therethrough for the pin 16, which passes through the hole 10 of the block 9. The center portion of the support and likewise the upper and 30 lower transverse extension of the same are preferably provided with beads or corrugations 17 and 18 respectively, and the upper transverse portion is also preferably turned substantially at right angles, as indicated 35 at 19, and is provided with pins 20, preferably stamped therefrom as shown. This provides a ledge-like support for the inner side of the heel to rest upon while the shoe is being displayed, the sole portion resting upon 40 the lower laterally extended portion 21.

The particular angle at which the shoe, or other article to be displayed may be varied by loosening up on the wing-nut 13, and adjusting the support in the bearing 10, after 45 which by tightening down upon the screw 13, the same will be presented at the desired angle. Also by similar manipulation of the screw 7, the article to be displayed may be rotated upon the vertical axis in case it is not 50 desired to turn the base of the stand, and the

same may be also elevated or depressed as may be desired.

Of course it will be understood that various modifications may be made in the construction and arrangement of parts without departing from the spirit of the invention as claimed.

We claim:

In a device of the class described, an integral I shaped stamping and a stand therefor, 60 said stamping having an embossing substantially I shaped in plan view following the contour of said integral shape, the lower portions of the upper arms of said stamping bent outwardly forming ledges.

65 In testimony whereof we hereunto affix our signatures.

MAURICE A. KONIKOFF.
HARRY R. KONIKOFF.
